UNITED STATES PATENT OFFICE.

GEORGE KOCH, OF SHELTON, CONNECTICUT, ASSIGNOR TO SIDNEY BLUMENTHAL & COMPANY, OF NEW YORK, N. Y., A CORPORATION OF NEW YORK.

WARP STOP-MOTION FOR LOOMS.

1,047,081.

Specification of Letters Patent. Patented Dec. 16, 1912.

Application filed October 14, 1911. Serial No. 654,700.

To all whom it may concern:

Be it known that I, GEORGE KOCH, a subject of the Emperor of Germany, and resident of Shelton, in the county of Fairfield 5 and State of Connecticut, have invented a new and useful Improvement in Warp Stop-Motions for Looms, of which the following is a specification.

My invention relates to a warp stop motion for looms, with the object in view of providing effective means for stopping the action of the loom when for any cause a warp thread breaks.

My present invention is illustrated in connection with what is known as the "Tonnar" loom for weaving a double pile fabric but I do not wish to limit it to this particular type of loom, as it may be successfully employed in connection with looms of various well known types.

In the accompanying drawings, Figure 1 is a view in side elevation, partly in section, of so much of a loom as will serve to show the practical application of my invention, 15 Fig. 2 is an enlarged partial plan view of the same, Fig. 3 is an enlarged partial vertical section of the same, Fig. 4 is a similar view showing one of the boxes depressed and the position of the parts immediately affected thereby, Fig. 5 is a partial plan view in detail of the tripping mechanism, Fig. 6 is a view of the same, in elevation partly in section, and Figs. 7, 8 and 9 illustrate in side elevation modified forms of the dogs 30 for setting in operation the stop motion.

In an application filed by me August 15, 1911, Serial No. 644,199, entitled Warp stop motions for looms, I showed, described and claimed mechanism for setting in motion 35 the stop motion by an electric current.

My present invention differs from the application above referred to in that it provides mechanical means for setting in operation the stop motion as distinguished from 40 electrical means.

The loom frame is denoted by 1, the gang of heddles by 2, the warp beams by 3 and 4, the lay beam by 5, the control lever by 6, the rocking lever for effecting the stopping 45 of the machine by 6*, the cam for operating said lever by 7, the hook on one arm of said lever by 8, and the rocking weft stop fingers by 9. These parts may be of any well known or approved form, such, for example, 50 as shown in the Tonnar Patent No. 716,352,

dated December 16, 1902. Uprights 10 and 11, fixed to a suitable horizontal support 12 and carrying brackets 13, 14, slots 15, 16, in the shorter arms of the brackets and 17, 18, in the longer arms of the brackets, horizontal boxes 19, 20, extending between the brackets 13, 14, hangers 21, 22, connected to a band 23 passing over the pulley 24 for maintaining the proper tension upon the warp threads 25, 26, the belt 27 leading 60 from a pulley 28 on the shaft 29, which rocks the heddles, to a pulley 30 suitably supported from the top frame of the loom and connected by a belt 31 with the shaft which carries the pulleys 24 and rods 32, 33, 65 extending along within the boxes 19, 20 which provides a series of dogs 34, each piece being mounted on the rod and free to swing thereon and each piece provided at its upper end, which projects slightly 70 through the top of the box, with an eye 35 through which a warp thread leading over the top of the box passes; may all be constructed, and arranged in a manner quite 75 similar to that shown and described in my pending application Serial No. 644,199, hereinabove referred to.

My present invention is directed particularly to the mechanism which mechanically coacts with the dogs 34, referred to in my former application as contact pieces, to effect the stopping of the loom when a warp 80 thread breaks.

Below the box 19 there is a skeleton frame consisting of horizontal arms 36, 37, projecting from uprights 38, 39, and connected by a rod 40, which rod 40 lies in the path of the lower ends of the dogs 34 when the latter are released from the warp threads and allowed to tilt into the position shown in 90 Fig. 3.

It is to be understood that there is a dog 34 for each of the warp threads and in the box 19, Fig. 3, one of these is shown in its normal position suspended by a warp thread 100 and another in its tilted position which it assumes when the warp thread breaks, such tilting of the dog carrying its nose outwardly and vertically over the rod 40 so that the downward movement of the box 105 will, when the lower end of the dog 34 has engaged the rod 40, carry the rod and the frame of which it forms a part, downwardly.

The uprights 38, 39, are fixed to a rock 110

shaft 41 suitably journaled in the uprights 10, 11 and the said rock shaft 41 is also provided with downwardly projecting parts, one of them being shown at 42, which correspond to the uprights 38, 39, and which may be as a matter of construction, parts of the same pieces as 38, 39, fixed to the rock shaft 41. These downwardly projecting parts, one of which is shown at 42, have 10 horizontal arms 43, 44, reaching out from them to support a rod 45 in position to engage the tilted dogs in the box 20 in a manner quite similar to that in which the rod 40 is engaged by the dogs in the box 19.

15 The rock shaft 41 has fixed to its outer end a depending arm, in the present instance a skeleton arm of loop form denoted by 46, and to its lower end there is attached a cord 47 which leads through a guide eye 48 on the 20 standard 10 and thence to a guide-eye 49 on the loom frame (see Fig. 1), and thence to the pawl 50 and its weighted tube (the latter corresponding to the pawl 52 and weighted tube 60 of my pending application 25, above referred to).

The depending loop arm 46 has a laterally widened central portion, the outer margins of which engage shoulders 52, 53, on angle shaped links 54, 55, pivoted to the standard 30 10 at 56, 57. The lower ends of these pivoted links are connected by a coil spring 58, which tends to draw them toward one another into contact with the opposite edges of the standard 10, which edges operate as 35 stops for limiting the inward swing of the links. When the arm 46 is tilted to one side, as shown in Fig. 4, it will be against spring pressure and the link 54 under its spring tension will tend to throw the arm 46 back 40 into the central position shown in Fig. 3.

In operation; when any one of the warp threads breaks and its dog 34 is allowed to tilt so as to bring the lower end of the dog into position to engage the rod 40 or the rod 45, the engagement with the rod will tilt the frame and rock shaft 41 thereby swinging the arm 46 attached to the rock shaft to the right or to the left and in whichever of these two directions it, the said arm, be 50 tilted, it will draw the cord 47 through the eye 48 and hence will pull down on the pawl 50, causing the latter to assume a position where it will be engaged by the hook 8 and the cam 7 will thereupon operate the control 55 lever 6 to throw the loom out of action.

The dog 34 may assume various forms other than that shown in Figs. 1 to 4 inclu-

sive. For example, as shown in Fig. 7, the eye, denoted by 59, may be open; or, as shown in Fig. 8, the eye, denoted by 60, may be open and also the hole through which the pivot rod 32 or 33 extends, may be open; or, as shown in Fig. 9, the eye may be closed and the hole through which the rod 32 or 33 extends, be open as shown at 61.

What I claim is:—

1. In a warp stop motion for looms, a swinging dog, held in position by a warp thread, means for raising and lowering the dog, a tilting frame in position to be operated by the dog when the latter is tilted out of normal position, a spring for returning the tilting frame to its normal position, a loom stopping mechanism and a flexible connection between the said tilting frame 75 and the loom stopping mechanism for actuating the latter.

2. In a warp stop motion for looms, a plurality of series of swinging dogs adapted to be held normally in position by warp threads, means for raising and lowering the dogs, a rock shaft, arms projecting in opposite directions from the rock shaft, rods carried by the arms in position to be engaged by any one of the dogs of the different series when tilted out of normal position, a spring actuated arm carried by the rock shaft and arranged to swing against spring tension in either of two opposite directions, loom stopping mechanism and a connection 90 between the said spring actuated arm and the loom stopping mechanism for actuating the latter.

3. In a warp stop motion for looms, a swinging dog adapted to be held normally 95 in position by a warp thread, means for raising and lowering the dogs, a tilting frame in position to be operated by the dog when tilted out of normal position, a stop mechanism, a cam, a rocking arm provided 100 with a hook for transmitting motion from the cam to the stop mechanism, a gravity pawl and a flexible connection between the said tilting frame and the gravity pawl for throwing the pawl into engagement with the hook.

In testimony, that I claim the foregoing as my invention, I have signed my name in presences of two witnesses, this 12th day of October, 1911.

GEORGE KOCH.
